COAT

Pauline Trigere, New York, N. Y.

Application January 27, 1951, Serial No. 13,994

Term of patent 7 years

(Cl. D3—4)

To all whom it may concern:

Be it known that I, Pauline Trigere, a citizen of the United States, residing in the Borough of Manhattan, city, county, and State of New York, have invented a new, original, and ornamental Design for Coat, of which the following is a specification, reference being had to the accompanying drawing, forming part thereof.

On the drawing,

Fig. 1 is a front view of a coat showing my new design;

Fig. 2 is a rear view of the coat shown in Fig. 1;

Fig. 3 is a front perspective view showing the coat of Fig. 1 turned to one side, and with one sleeve raised; and

Fig. 4 is a perspective view of the coat shown in Fig. 1, at an angle to the rear, and with the collar turned up.

I claim:

The ornamental design for a coat, as shown.
PAULINE TRIGERE.
